(57) **CLAIM**

The ornamental design for a power bank, as shown and described.

DESCRIPTION

FIG. 1 is a front and top perspective view of a power bank showing my new design, with the power bank in a first state; FIG. 2 is a rear and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a top and right perspective view of a power bank in a second state. The broken lines in the drawings depict portions of the power bank that form no part of the claimed design.

1 Claim, 9 Drawing Sheets
